UNITED STATES PATENT OFFICE.

SHINICH MATSUGAKI, OF TOKYO, JAPAN.

BRUSH.

1,387,063.

Specification of Letters Patent. Patented Aug. 9, 1921.

Application filed December 21, 1920. Serial No. 432,277.

To all whom it may concern:

Be it known that I, SHINICH MATSUGAKI, a subject of the Emperor of Japan, residing at No. 18 Yarai-machi, Ushigome-ku, in the 5 city of Tokyo, Empire of Japan, have invented certain new and useful Improvements in Brushes, of which the following is a specification.

This invention relates to a brush and more 10 especially to a pocketable brush wherein the bristle tuft is adapted to be drawn into a case or exposed therefrom by means of the cap of the brush. The object of the invention is to provide a brush in which the bristle tuft is well protected when not in use, and to provide such a brush which can be 15 easily handled and is simple in construction.

The construction of the brush according 20 to this invention is illustrated in the accompanying drawing in which—

Figure 1 shows the brush ready for use the bristles being exposed.

Fig. 2 shows partly in section the brush 25 with the bristles drawn into the case.

Fig. 3 is a longitudinal section of Fig. 1.

Fig. 4 is an end view of Fig. 2, and Fig. 5 is another end view of Fig. 2.

Similar references refer to similar parts 30 throughout the drawing.

Referring to the drawing, 1 is an open case having a slot *a* in one side and containing a sliding box 2. The latter is provided in one side with a pin *b* engaging the said 35 slot *a* in the case 1 and is fitted with another pin *c* at one end. (Figs. 2 and 5.) At the other end the sliding box 2 carries the bristles 3 fixed to a tube or suitable socket member 4. The sliding box 2 is also provided with a cavity *d* adapted to be engaged 40 by a projection formed in the inner side of the case 1, said projection being yieldingly pressed into the cavity *d* when the bristles are in exposed position, thereby preventing 45 the latter from unnecessary movement.

5 is a cap with its one half larger than the other. By the larger part said cap is adapted to engage the outer side of the case 1, as shown in Fig. 2, and by the smaller part it is 50 adapted to engage the inner side of the case 1, as shown in Figs. 1 and 3. At the end of

the smaller part the cap 5 is provided with an elongated slot *e* for receiving the pin *c* of the case 1. At both ends the said slot *e* is enlarged and is of sufficient size so 55 that the pin *c* can freely pass through, the latter is then engaged by the reduced part of the slot *e*.

From the foregoing it will be noted that in this brush the bristle may be withdrawn 60 into the case 1 or be pushed out therefrom. This is effected by connecting the smaller end of the cap 5 to the rear end of the sliding box, the pin *c* of the former engaging the slot *e* of the latter, and pushing the cap 65 5 into the case 1 or pulling it out therefrom. The slot *a* in the case 1 and the pin *b* in the sliding box 2 serve to limit the movement of the sliding box relative to the case.

When the bristle 3 is drawn into the 70 case it is covered by the cap 5, as shown in Fig. 2, thus the brush may be pocketed or otherwise carried without injuring the bristle and collecting dust thereon.

For pushing out or exposing the bristle 75 3, the pin *c* is passed through one enlarged end of the slot *e* and engaged by the reduced part thereof, thus connecting the cap 5 to the sliding box 2, and then the cap 5 is pushed into the case 1, whereby the bristle 3 80 will be exposed ready for use. And vice versa for withdrawing the bristle 3 into the case 1.

What I claim is:

1. A pocket brush comprising a case open 85 at its ends, a member slidable in said case and having bristles which may be projected beyond one end of the case, and a cap having a portion adapted to fit in the case, and detachably connected to said slidable member, 90 said cap also having a portion adapted to fit over the case, when said cap is detached from said slidable member and to close the first named end of the case and protect the bristles. 95

2. A pocket brush comprising a case open at its ends, a member slidable in said case and having bristles which may be projected beyond one end of the case, said case and member having means to limit the extent of 100 movement of said member, and a cap having a portion adapted to fit in the case, and de-

tachably connected to said slidable member, said cap also having a portion adapted to fit over the case, when said cap is detached from said slidable member and to close the 5 first named end of the case and protect the bristles.

In witness whereof I have hereunto set my hand in the presence of two witnesses.

SHINICH MATSUGAKI.

Witnesses:

E. L. MURRAY,
T. C. SMITH.
